(57) **CLAIM**

The ornamental design for a traffic channeling device, as shown and described.

DESCRIPTION

FIG. 1 is a front, left perspective view of our new design for a traffic channeling device;

FIG. 2 is a rear, right perspective view of our new design for a traffic channeling device;

FIG. 3 is a front elevational view of our new design for a traffic channeling device;

FIG. 4 is a rear elevational view of our new design for a traffic channeling device;

FIG. 5 is a side elevational view of our new design for a traffic channeling device from the right side of FIG. 1, the left sided being a mirror image thereof;

FIG. 6 is a top plan view of our new design for a traffic channeling device; and,

FIG. 7 is a bottom plan view of our new design for a traffic channeling device.
